UNITED STATES PATENT OFFICE.

JOHN GRIFFIN, OF LOUISVILLE, KENTUCKY.

MODE OF REGULATING THE SPEED OF VEHICLES MOVED BY MECHANICAL POWER.

Specification of Letters Patent No. 31,595, dated March 5, 1861.

To all whom it may concern:

Be it known that I, JOHN GRIFFIN, of Louisville, in the county of Jefferson and State of Kentucky, have invented a new and Improved Mode of Regulating the Speed of Vehicles Moved by Mechanical Power; and I do hereby declare that the following is full, clear, and exact description of the same, reference being had to the annexed drawings, making a part of this specification, in which—

Figure 1, is a side sectional view of a steam carriage with my invention applied to it, taken in the line x, x , Fig. 3. Fig. 2, a transverse vertical section of the same, taken in the line y, y , Fig. 1; Fig. 3, a plan or top view of the same; Fig. 4, a detached sectional view of a portion of the same, taken in the line z, z , Fig. 1; Fig. 5, a detached view of levers pertaining to the invention.

This invention consists in an improved arrangement of means for varying the speed of the carriage or vehicle as circumstances may require, a slow speed being frequently necessary and at other times a quick speed.

The invention is more especially designed to be applied to steam carriages for conveying steam cotton picking devices.

To enable those skilled in the art to fully understand and construct my invention I will proceed to describe it.

A, represents a platform which is mounted on wheels B, B, C, C, and has a rectangular framing D', on its upper surface. The wheels B, B, support the front part of the framing, while the back wheels C, C, are caster wheels and support the back part of the framing.

On the platform A, there is placed a steam boiler G. This boiler is placed over the axles D, of the wheels B.

H, H, are two steam cylinders the pis-

ton rods I, I, of which are connected to one end of walking beams J, J, the opposite ends of which have connecting rods K, K, attached. The lower ends of the rods K, are connected to cranks L, on the axles D, D, that is to say, when the carriage is to be moved from place to place and locomotion is only to be considered or desired. This arrangement it will be seen will admit of a quite rapid movement of the carriage.

When the machine is at work a comparatively slow motion of the carriage is required, and this is effected as follows: The connecting rods K, K, are detached from the cranks L, and connecting rods M, M, which are attached to the walking beams J, J, near the rods K, are connected at their lower ends to cranks N, which are on shafts O, on the platform A. These shafts O, are connected by gearing g, with vertical shafts P, the lower parts of which have screws h, on them and these screws gear into toothed wheels Q, on the axles D, D. By this arrangement it will be seen a slow speed may be given the carriage when required. When the rods M, are disconnected from their cranks N, the screws h, of the shafts P, are thrown out of gear with the wheels Q, by means of levers A*, the shafts P, being stepped in shifting bars.

Having thus described my invention what I claim as new and desire to secure by Letters Patent; is,

The arrangement of the two connecting rods K, M, attached respectively to the cranks L, N, of the axles D, and shafts O, the latter when in use being connected to the axles by the gearing g, h, Q, substantially as and for the purpose set forth.

JOHN GRIFFIN.
